CLAIM

The ornamental design for a suspended holder for plants, candles or the like, as shown.

DESCRIPTION

FIG. 1 is a front elevational view of a suspended holder for plants, candles or the like showing our new design;
FIG. 2 is a side elevational view taken from the right of
FIG. 1;

FIG. 3 is a rear elevational view thereof;

FIG. 4 is a side elevational view taken from the left of
FIG. 1;

FIG. 5 is a bottom plan view thereof;

FIG. 6 is a top plan view thereof.

FIG. 1

FIG. 2

FIG. 3

FIG. 4

FIG. 5

FIG. 6
